UNITED STATES PATENT OFFICE.

JOHN H. BRETT, OF HARTFORD, CONNECTICUT.

SOUNDING TOY.

Application filed September 17, 1921. Serial No. 501,371.

To all whom it may concern:

Be it known that I, JOHN H. BRETT, a citizen of the United States, residing at Hartford, in the county of Hartford and State of Connecticut, have invented certain new and useful Improvements in Sounding Toys, of which the following is a specification.

This invention relates to a sounding toy such as will emit a musical tone or tones when subjected to the proper action which in the present case is by rotating the device. Among the objects of the invention are the provision of an article of the character set forth, which is capable of inexpensive construction, which can be readily made and which can be easily operated usually by hand.

In the drawings accompanying and forming part of the present specification, I have shown in detail one of the several forms of embodiment of the invention which to enable those skilled in the art to practice the same will be set forth fully in the following description. Obviously I am not restricted to such disclosure. I may depart therefrom in a number of respects within the scope of the invention defined by the claims following said description.

Referring to said drawings:—

Figure 1 is an elevation of a toy involving the invention.

Fig. 2 is a vertical section on the line 2—2 of Fig. 3.

Fig. 3 is a vertical section on the line 3—3 of Fig. 2.

Figs. 4 and 5 are vertical sections on the lines 4—4 and 5—5 respectively of Fig. 2.

Like characters refer to like parts throughout the several views.

The device involves a suitable hollow body such as that denoted in a general way by 2, and which with certain portions thereof may be made from proper material such as any one of several sheet metals. As shown the body is made up of two like concave-convex sections 3 generally with their concave sides next to each other with their edges interlocked usually, by spinning the marginal portion of one of said sections 3 fitting over the corresponding portion of the complementary section so as to produce between them a chamber to receive within it what I term an impeller and certain adjunctive parts. The sections 3 have generally centrally upon their outer sides the bosses 4 transversely aligned and with which the rotating means of

whatever character it may be is desirably connected.

The rotating means usually consists of cords 5 in loop formation, the inner bights being extended through perforations in the outer portions of the bosses 4, which is to be understood are hollow. It might be stated at this point that the toy has air inlet holes and air outlet holes for the entrance and discharge respectively of air. The air outlet holes 2' of which there are usually several, are desirably formed in the peripheral portion of the body 2 which is slotted to form said holes and which are generally arranged in pairs. The inlet openings 4' are usually formed in the bosses 4, the inlets or air supply openings being generally located back of the tips or crowns of the bosses.

Practically centrally disposed in the body 2, is the shaft or spindle 8, the terminal portions of which are rotatively supported by reed-carriers which usually consist of circular plates or disks 9 fixedly set in the inner ends of the hollow bosses 4, and each provided with several external reeds 10, covering slots 10' therein. Endwise movement of the shaft or spindle 8 is prevented in some convenient way as by collars 11 rigidly fastened thereto and abutting the respective reed carriers, plates or disks 10.

The body 2 receives within it an impeller 12 ordinarily made from some sheet metal stock and having on its sides the wings or blades 13 which positively direct the air drawn into the body 2 against the reeds 10 to sound the reeds, the air after it has exercised such function, passing to atmosphere by way of the outlets 2'.

The shaft or spindle 8 is provided near its opposite ends with segmental, flat valves as 14 rigid therewith and oppositely placed so that as the valves turn with the shaft or spindle they alternately render the reeds 10 effective to be sounded by blasts of air, passing through the slots 10'.

The impeller 12 usually is composed of two circular members 12 fitted face to face flatwise with their marginal portions clamped by and between the sections of the body 2. The circular members 12 have on their exterior, the blades or wings 13, in order to positively drive out air as the toy is rotated, by way of the slots 2' directing the air laterally through the slots 10' of the reed-carriers 10, by reason of which the reeds are sounded by the air which subsequently

passes to atmosphere by way of the openings 2'.

The shaft or spindle 8 rigidly carries the valves 14 oppositely disposed and which are rendered alternately effective by the arms 16 engageable by the impeller 13 as the same is oppositely rotated, said arms being fastened to the shaft 8.

What I claim is:—

- 10 1. A sounding toy comprising a hollow body having air inlets and air outlets, the body having means to be rotated oppositely by cord means, a disk in the body having slots and also having reeds opposite the respective slots, and an impeller in the body, having wings to direct air against the reeds.
2. A sounding toy comprising a hollow body having air inlets and air outlets, the body having means to be rotated oppositely by cord means, a disk in the body having slots and also having reeds opposite the respective slots and an impeller in the body,

having wings to direct the air against the respective reeds, and valve means for rendering the reeds alternately effective and ineffective in groups.

3. A sounding toy comprising a hollow body, the opposite sides of which are provided with outwardly extended bosses, having air inlets and also having cord receiving means, the body having in its peripheral portion, air outlets, disks, supported at the inner ends of the bosses and having slots, and also having reeds, opposite the slots, a shaft supported for rocking movement by the reed carrying plates, and valves rotative with the shaft, for rendering the reeds alternately effective.

In testimony whereof I affix my signature.

JOHN H. BRETT.

In presence of—

Miss M. LONG,
HEATH SUTHERLAND.
